[57] CLAIM

The ornamental design for hair spray shield, as shown and described.

DESCRIPTION

FIG. 1 is a perspective view of hair spray shield showing our new design;

FIG. 2 is a top plan thereof;

FIG. 3 is a front elevational view thereof;

FIG. 4 is a left side elevational view thereof; the right side elevational view being a mirror image;

FIG. 5 is a rear elevational view thereof; and
FIG. 6 is a bottom plan view thereof.

The broken line showing of environment in FIG. 1 is for illustrative purposes only and forms no part of the claimed design.

FIG. 1

FIG. 2

FIG. 3

FIG. 4

FIG. 5

FIG. 6
